UNITED STATES PATENT OFFICE

CHARLES N. PROUTY, OF SPENCER, MASSACHUSETTS, ASSIGNOR TO ISAAC PROUTY & CO., INC., OF SPENCER, MASSACHUSETTS, A CORPORATION OF MASSACHUSETTS

BACKSTAY FOR SHOES

Application filed June 5, 1928. Serial No. 283,027.

This invention relates to the manufacture of men's shoes and particularly to the manufacture of high shoes designed for use by soldiers, policemen or other persons who 5 habitually wear leather puttees.

It has been found that such leather puttees bear against the back stay of the shoe in such a manner as to chafe and cut the stitches at each edge thereof, requiring frequent re- 10 pairs and re-stitching at this point of engagement.

It is the general object of my invention to provide an improved construction by which such excess wear of the back stay and stitching 15 is greatly reduced.

More specifically, the invention in its preferred form relates to the provision of an improved form of back stay and to an improved disposition of stitching relative to the 20 back center line of the shoe.

My invention further relates to details of construction which will be hereinafter described and more particularly pointed out in the appended claim.

25 A preferred form of the invention is shown in the drawings in which

Fig. 1 is a side elevation of a shoe embodying my improvements;

Fig. 2 is a partial rear view thereof, looking in the direction of the arrow 2 in Fig. 1, and

Fig. 3 is an elevation of the back stay.

Referring to the drawings, I have shown 35 a man's high shoe of usual construction and comprising a vamp 10 and quarters 11. A back stay 12 covers the rear center line of the shoe and secures the two quarters 11 firmly together.

40 My improved back stay, as shown in Fig. 3, is provided with substantial lateral projections 15 at a point intermediate the ends thereof, these projections being preferably formed by smooth and continuous curves 45 along the edges of the back stay and in-

creasing the stay to substantially double width at its middle portion.

In securing the back stay 12 to the quarters 11, the rows of stitching 16 follow closely along the edges of the back stay, and curve 50 outward and away from the center line with the lateral projection 15. The stitching 16 is thus projected forward of the shoe and away from the back center line of the shoe at the point engaged by the lower edge of a 55 leather puttee P, as indicated in Fig. 1. Such puttee is commonly formed of relatively stiff material, which bows outward more or less away from the sides of the shoe but which closely engages the shoe at the center of the 60 back, at a point located above the counter area of the shoe.

By thus projecting the stitching forward away from the back center line, the stitches are positioned at points where the puttee 65 bows outward and where it does not rest against the stitching with sufficient pressure to cause excessive wear. By this simple change in construction, I thus avoid the excessive wear of the stitches at the back seam 70 and substantially prolong the life of the shoe before repairs become necessary.

My improvement has been found of practical and commercial value and is greatly appreciated by persons having occasion to 75 habitually wear the combination of high shoes and leather puttees.

Having thus described my invention and the advantages thereof, I do not wish to be limited to the details herein disclosed otherwise than as set forth in the claim, but what I claim is:—

In a high shoe, a vamp, quarters, and a back stay secured by stitching to said quarters, said back stay being substantially 85 doubled in width by laterally projecting portions at the point of greatest pressure and wear thereon from the lower edge of a puttee, above the counter area of the shoe, said back stay being secured to said quarters 90

by rows of stitching following closely adjacent the edge portions of said back stay and projecting portions, said projecting portions being relatively narrow and of limited longitudinal extent and projecting forwardly a sufficient distance to remove the stitching therearound from said point, and said back stay being abruptly reduced to substantially normal width immediately above and below said projections.

10 In testimony whereof I have hereunto affixed my signature.

CHARLES N. PROUTY.
